UNITED STATES PATENT OFFICE.

THEODORE F. PHILIPPI, OF EAST ST. LOUIS, ILLINOIS.

CRUSHER.

1,358,782.

Specification of Letters Patent. Patented Nov. 16, 1920.

Application filed December 19, 1917. Serial No. 207,965.

To all whom it may concern:

Be it known that I, THEODORE F. PHILIPPI, a citizen of the United States of America, a resident of East St. Louis, in the county of St. Clair, State of Illinois, have invented certain new and useful Improvements in Crushers, of which the following is a full, clear, and exact description, reference being had to the accompanying drawings, forming a part of this specification.

My invention relates to improvements in crushers, the object being to provide a simple and very efficient means for crushing, or crushing and pulverizing, various kinds of material, such for example as marble chips. The preferred form of the invention comprises a rotatable crushing device arranged within a rotatable annular housing. The material to be crushed and pulverized is introduced through a central intake opening in the rotatable housing, and the pulverized product is drawn out, by suction, through a central discharge opening. The novelty lies in certain combinations of elements and certain details of construction which will be hereinafter described and set forth in the claim.

Figure I is a side elevation of a crusher and pulverizer constructed in accordance with my invention.

Fig. II is a vertical section.

Fig. III is a section taken on the line III—III, Fig. II.

The structure herein shown comprises bearings 1, a horizontal shaft 2 rotatably mounted in said bearings, a drive pulley 3 fixed to said shaft, a crushing device comprising a spider 4 secured to the shaft 2, pins or fingers 5 extending laterally from the arms of the spider 4, and crushing rings 6 loosely mounted on said pins 5. These pins are connected together and reinforced by a retaining ring 7 (Figs. I and II), the extended end portions of said pins being reduced and provided with screw threads. Nuts 8 are fitted to the threaded ends of pins 5 to secure the retaining ring 7. The relatively small crushing rings 6 are loosely mounted between the spider 4 and the retaining ring 7.

The crushing elements just described are surrounded by a rotatable annular housing A, mounted in a stationary circular support 9, provided with bearings 10 for anti-friction rollers 12 which engage the pe-

ripheral face of said rotatable housing, the latter having guide flanges 13 at opposite sides of the rollers. The anti-friction rollers 12 allow the annular housing to turn 60 freely around the internal crushing elements, and the guide flanges 13 coöperate with the rollers to secure the housing to the stationary supporting ring 9.

A large crushing ring 14, carried by the 65 housing, coöperates with the relatively small crushing rollers 6 to pulverize the material in the housing. This large crushing ring 14 is made of a number of arcuate sections 14' (Fig. III) secured to the peripheral 70 wall of the housing by means of radial screws 15, the heads of the screws being exposed at the periphery of the housing, and the arcuate sections 14' being threaded to receive the screws. These arcuate sections 75 as well as the small crushing rings 6, are preferably made of hardened metal.

The opposite side walls of the housing are preferably offset and provided with converging annular faces 16 and 16' (Fig. 80 II) whereby the material to be crushed is directed to the segmental crushing ring 14.

One side wall of the rotatable housing is provided with a central intake opening 17 (Fig. II) and an approximately L-shaped 85 stationary intake tube, or chute, 18 extends into said opening. This stationary intake member is secured to one of the bearings 1, as shown in Fig. II. The rotatable housing is also provided with a central discharge 90 opening, and an approximately L-shaped suction tube 19 (Fig. II) extends into this opening. The pulverized material can be drawn through the suction tube 19 by means of a suction fan, as indicated in Fig. II. 95 This suction tube 19 is stationary and it may be provided with a bracket 20 secured to one of the bearings 1.

The power transmission devices include the shaft 2 which extends through the suction tube 19 and also through the central openings in the rotatable housing, a sprocket wheel 21 secured to said shaft, a chain 22 whereby power is transmitted from said sprocket wheel to a larger 100 sprocket 23 on a shaft 24, a pinion 25 secured to said shaft 24, and a large gear ring 26 meshing with said pinion. The large gear ring is secured to one side of the rotatable annular housing. The internal 110 crushing elements revolve at a relatively high speed, while the annular housing turns

at a much lower speed. It will also be observed that the housing and internal crushing device are rotated in opposite directions.

I claim:

- 5 A crusher comprising a housing, a rotatable carrier arranged in said housing, pins secured to and extending laterally from said carrier, the extended ends of said pins being reduced to form shoulders, a retaining ring
10 mounted on the reduced ends of said pins.

securing means on said reduced ends, said retaining ring being confined between the said shoulders and said securing means, and crushing means loosely mounted upon the said pins between the rotatable carrier and 15 the retaining ring.

In testimony that I claim the foregoing I hereunto affix my signature.

T. F. PHILIPPI.
